GRILL SCRAPER AND CLEANER COMBINATION

John Prunchak, 1013 Wymore St.,
Pittsburgh, Pa. 15220

Filed Jan. 18, 1966, Ser. No. 666

Term of patent 7 years

(Cl. D9—6)

Fig. 3

The broken lines shown in FIG. 1 are for illustrative purposes only.

I claim:

The ornamental design for a grill scraper and cleaner combination, as shown and described.
